DESIGN FOR A SHOELACE

Coleman S. Winchester, Brockton, Mass.

Application September 22, 1939, Serial No. 87,348

Term of patent 14 years

To all whom it may concern:

Be it known that I, Coleman S. Winchester, a citizen of the United States, residing at Brockton, in the county of Plymouth and State of Massachusetts, have invented a new, original, and ornamental Design for Shoelaces, of which the following is a specification, reference being had to the accompanying drawing, forming a part thereof.

The figure is a plan view of a shoelace showing my new design, the same being of contrasting colors and joined together in the manner shown.

I claim:

The ornamental design for a shoelace, as shown and described.

COLEMAN S. WINCHESTER.
